United States Patent Office

Des. 227,419
Patented June 26, 1973

227,419

MOCCASIN

Horst Lachmayr, Columbus, Ohio, assignor to SCOA
Industries, Inc., Columbus, Ohio

Filed Feb. 25, 1972, Ser. No. 229,612

Term of patent 7 years

Int. Cl. D2—04

U.S. Cl. D2—268

Fig. 1

Fig. 2

FIG. 1 is a front perspective view of a moccasin showing my new design.

FIG. 2 is a rear perspective view thereof.

FIG. 3 is a bottom plan view of the upper and sole of my design in open flat condition.

FIG. 4 is a side elevation thereof.

I claim:

The ornamental design for a moccasin, as shown.
